(57) **CLAIM**

The ornamental design for a faceplate for wireless earphone, as shown and described.

DESCRIPTION

FIG. 1 is a top, front, and left perspective view of a faceplate for wireless earphone showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the faceplate and the wireless earphone that form no part of the claimed design, namely, in FIGS. 2-5, the broken lines showing portions of the faceplate form no part of the claimed design, and in FIGS. 1-7, the broken lines showing the wireless earphone form no part of the claimed design but depict the environment of the claimed design.

1 Claim, 7 Drawing Sheets
